(57) **CLAIM**

The ornamental design for a outlet harness device, as shown and described.

DESCRIPTION

FIG. 1 is a side elevation view of an outlet harness device; FIG. 2 is an opposing side elevation view thereof; FIG. 3 is a front elevation view thereof; FIG. 4 is a rear elevation view thereof; FIG. 4 is a side elevation view thereof; FIG. 5 is top plan view thereof; FIG. 6 is a bottom plan view thereof; FIG. 7 is a bottom perspective view thereof; and, FIG. 8 is a front elevation view of an outlet harness device positioned over a power control device (in broken line) plugged into an electrical outlet.

The broken line in the figure drawings represents unclaimed environment only and forms no part of the claimed design.
